CLOSURE CAP FOR CANS OR THE LIKE

Florence S. Yoder, Long Beach, Calif.

Application January 14, 1958, Serial No. 49,252

Term of patent 14 years

(Cl. D58—26)

Figure 1 is a perspective view of a closure cap for cans or the like, showing my new design;

I claim:

The ornamental design for a closure cap for cans or the like, substantially as shown.
